(57) **CLAIM**

The ornamental design for a game console docking station, as shown and described.

DESCRIPTION

FIG. 1 is a perspective of the game console docking station showing my new design;

FIG. 2 is a perspective thereof from another angle;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the game console docking station is being used.

The broken lines show portions of the game console docking station that form no part of the claimed design.
